UNITED STATES PATENT OFFICE.

JOHN DIAOVSKY, OF PASSAIC, NEW JERSEY, ASSIGNEE, BY DIRECT AND MESNE ASSIGNMENTS, TO D. S. W. MANUFACTURING AND TRADING CORPORATION, OF NEW YORK, N. Y., A CORPORATION OF NEW YORK.

GAS-TURBINE.

1,149,252.

Specification of Letters Patent. Patented Aug. 10, 1915.

Application filed November 15, 1913. Serial No. 801,105.

To all whom it may concern:

Be it known that I, JOHN DIAOVSKY, a citizen of the United States, residing at Passaic, Passaic county, New Jersey, have 5 invented a new and useful Improvement in Gas-Turbines, of which the following is a full, clear, and exact description.

My invention relates to improvements in gas turbines, that is turbines which operate 10 by the explosion of gaseous fuel, or by compressed air or other fluid pressure, and the object of my invention is to produce a very simple and efficient machine in which the exploded charge is admitted near the center of 15 the machine and on the surface of the rotor, and then permitted to escape toward both ends of the machine so that it will operate by impact and expansively on a series of turbine blades, and thus impart rotary motion 20 to the rotor, although the intake may be at the ends and the exhaust in the center, or the intake at one end and the exhaust at the other. The first two arrangements above noted cause a balanced pressure, as the gases 25 will be expanding in opposite direction from the center toward the blades, thus eliminating end friction.

Another important feature of my invention is that I have a hollow rotor, and provide for driving a current of air or other cooling fluid through the rotor, thus rapidly cooling the machine so that water-jacketing 30 is not necessary, although the outer cylinder can be jacketed in the usual way if desired.

In providing for the expansion of gases and the intake of the machine, I arrange one or more fuel explosion chambers on the exterior of the machine, and have these connect with ports in the central chamber on the exterior of the rotor, so that the exploded gases from the exterior chamber will be conducted to the inner chamber and from thence to the blades.

Reference is to be had to the accompanying drawings forming a part of this specification, in which similar reference characters indicate corresponding parts in all the views.

Figure 1 is a longitudinal section of the machine embodying my invention. Fig. 2 is a cross section on the line 2—2 of Fig. 1. Fig. 3 is an end view of the plate and frame

covering the rotor end. Fig. 4 is a view similar to Fig. 3 but with the blades removed. Fig. 5 is a detail section showing the arrangement of one of the expansion chambers. Fig. 6 is a detail section of a portion of the fan at the end of the rotor.

The turbine has a suitable casing 10 which is preferably provided with longitudinal strengthening ribs 11 and spaced apart within the cylinder is a cylindrical rotor 12 which is hollow so that the air or other cooling fluid can pass through it, and is formed of the outer shell or cylinder 13, the inner box 14 which receives the shaft 15 of the turbine, and the ribs 16 which connect the members 13 and 14, and serve to brace the rotor.

Spaced apart around the middle portion of the machine are the expansion or combustion chambers 17, which can be supplied in any usual way with explosive charges, and there can be any desired number of these chambers. They connect through ports 18 with the inner chamber 21 presently referred to, and the passage through the port 18 is controlled by a flap valve 19, which can be backed by a spring 20. Obviously any suitable valve can be substituted for the valve 19, and the charge can be supplied to the chamber 17 in any usual or preferred manner. The inner or distributing chamber 21 connects as stated with the chamber 17, and is formed between the inner grooved ring 22 which fits around the middle portion of the rotor and an outer ring 23, these rings being shown best at the bottom of Fig. 1. It will be seen that by changing the sizes of these rings, that is the thickness of them, the size of the chamber can be made as desired.

From the chamber 21 the expanding gases pass toward the ends of the machine through the turbine blades, and so give motion to the rotor. These turbine blades can be of any usual kind, but I prefer the type of blade and ring shown in my application for Letters Patent of the United States No. 100 778,627, filed July 12, 1913. The general arrangement is shown best in Fig. 1. Next the cylinder 11 are a series of fixed rings 24 carrying deflecting blades 25, and these rings are spaced apart by the spacing rings 26. The several rings 24 and 26 are held

snugly together by the ring nuts 27 at the ends of the cylinder 11, and it will be seen that this arrangement provides for tightening the rings, and at the same time enables easy access to be had to them in case repairs are necessary. On the rotor are a series of running rings 28 having blades 29, and these are spaced apart by spacing rings 30, a series of spacing and running rings being held together by nuts 31 at the ends of the rotor, which fasten the several rings in place. The blades 25 deflect the gases against the blades 29 of the rotor rings, so that motion is imparted to the rotor, and by reference to Fig. 1 it will be seen that the blades grow larger, that is longer, toward the ends of the turbine, to provide for the expansion of gases. It will be seen that this arrangement makes a very simple construction in which the several parts are readily accessible, and in which the rings can be nicely centered and securely held.

When the gases reach the ends of the machine they are expanded to such an extent that they have no appreciable pressure, and the exhausted gases are discharged in the channels 32 of the end plates 33 which are secured to the ends of the turbine, and can be fastened in any convenient manner. A good way is to provide flanges 34 on the plates 33 which meet flanges 35 on the cylinder 10, and the two flanges are fastened together by bolts 36. The exhausted gases pass down and out through ports 33^a in the legs of the casing.

To provide against any leakage of gases, the plates 33 are provided with lips 37 which enter corresponding recesses in the nuts 31, and the plates also have inner lugs 38 which abut with corresponding shoulders 39 on the rings 40 which are formed on the plates 39^a, and these are secured to the ends of the rotor. The plates 39^a have openings 41 therethrough, and are provided with fan blades 42 adjacent to the openings, so that when the rotor revolves, a current of air is drawn rapidly through the rotor and serves to cool the machine. I have shown plates 39^a and corresponding fans at each end of the machine so as to provide for the air current in case the engine is reversed, but ob-

viously the fan can be arranged at one end if desired.

From the foregoing description it will be seen that I have provided an extremely simple machine which is evenly balanced, in which all the parts are accessible, and in which the expanding gases are used to the best advantage, and it will be seen that the arrangement for connecting the plates 33 carrying the exhaust to the channels is such as to prevent leakage of exhausted gases, especially as they will carry very little pressure.

I claim:—

1. A gas turbine comprising a rotor, a hollow cylinder inclosing the rotor and spaced apart therefrom, banks of turbine blades operatively connected with the rotor and cylinder, ring nuts arranged at the ends of the rotor and cylinder and connecting with said rotor and cylinder respectively to hold the blades in place, end plates having exhaust channels therein, said end plates being connected to the cylinder and rotor and having annular lips entering corresponding recesses on the rotor nuts, a distributing chamber arranged within the cylinder and adapted to discharge directly against the adjacent turbine blades, and an exterior explosion chamber opening directly into the distributing chamber.

2. A gas turbine comprising a rotor, a cylinder spaced apart from the rotor, banks of turbine blades operatively connected with the rotor and cylinder, means for directing gases directly against the blades, plates at the ends of the cylinder and rotor having exhaust channels to carry away the exploded gases from the blades, ring nuts connected respectively to the end portions of the cylinder and rotor to hold the blades in place, annular lips on the end plates to fit corresponding recesses on the rotor ring nut, an annular shoulder on each of the end plates, and flanges connected to the rotor and overlapping the aforesaid shoulders on the end plates.

JOHN DIANOVSKY.
